UNITED STATES PATENT OFFICE.

WILLIAM H. BRUNSON, OF PUEBLO, COLORADO.

RIGID COUPLING.

1,281,284.

Specification of Letters Patent. Patented Oct. 15, 1918.

Application filed February 25, 1918. Serial No. 219,062.

To all whom it may concern:

Be it known that I, WILLIAM H. BRUNSON, a citizen of the United States, residing at Pueblo, in the county of Pueblo and State 5 of Colorado, have invented certain new and useful Improvements in Rigid Couplings, of which the following is a specification, reference being had to the accompanying drawings.

10 This invention relates to certain improvements in rigid couplings and it is an object of the invention to provide a novel and improved means whereby the meeting ends of the sections of a drill rod may be conveniently connected or coupled one to the other 15 and whereby said connection or joint is rigid.

It is also an object of the invention to provide a novel and improved joint of this 20 general character wherein the strokes of the rod serve to tighten and materially facilitate the effectiveness of the coupling.

The invention consists in the details of construction and in the combination and arrangement of the several parts of my improved rigid coupling whereby certain important advantages are attained and the device rendered simpler, less expensive and otherwise more convenient and advantageous 30 for use, as will be hereinafter more fully set forth.

The novel features of my invention will hereinafter be definitely claimed.

In order that my invention may be the 35 better understood, I will now proceed to describe the same with reference to the accompanying drawings, wherein:

Figure 1 is a view in section of the meeting ends of the sections of a rigid drill rod 40 illustrating a coupling constructed in accordance with my invention; and

Fig. 2 is a view in elevation of my improved coupling as herein embodied with a portion broken away.

45 As disclosed in the accompanying drawings the sections 1 of a drill rod have their meeting ends provided with the reduced extensions 2 having their peripheries inwardly flared as indicated at 3.

50 The sections 1 of the rod when in operative relation are in vertical alinement and the lower peripheral portion of the upper section immediately adjacent its extension 2 is provided with the threads 4 with which 55 is engageable the locking member or nut 5. The member 5 is herein disclosed as annular

in form and provided in its periphery with the recesses or sockets 6 so that a spider wrench or the like may be properly engaged therewith to effect the requisite rotation. 60

S denotes a sleeve split longitudinally to afford two separable sections 7 preferably of duplicate configuration and the inner walls of said sections 7 from the longitudinal center thereof are tapered in opposite 65 directions so that said sections will snugly engage the peripheries of the extensions 2 of the meeting ends of the rod sections 1. The sleeve S when assembled has its outer walls tapered with the smaller diameter upwardly directed as indicated at 8 and said sleeve S is of such a major diameter as to extend slightly beyond the peripheries of the sections 1.

C denotes a collar having its bore 9 75 tapered so as to snugly receive the sleeve S and whereby it will be at once self-evident that as the collar C is forced downwardly the sections 7 of the sleeve S tightly engage the extensions 2 of the sections 1 and which 80 results in a rigid and solid connection between the meeting ends of the sections 1.

In applying my improved coupling the locking member 5 is disengaged from the threads 4 and moved upwardly of the upper section 1. The collar C is then passed upwardly of said upper section 1 and the sleeve S applied. The collar C is then dropped down over the sleeve S and is firmly forced into engagement with the sleeve by 90 several blows from a sledge or other implement. The locking member 5 is then engaged with the threads 4 and brought into contact with the upper end of the collar C. It will also be self-evident that if this connection should not connect the meeting ends of the sections 1 in absolute rigidity a few working strokes of the rod will result in the requisite downward movement of the collar C to assure such connection. In order to 100 hold the sleeve S and the sections 1 against relative rotation, I find it of advantage to employ in connection therewith a locking key 10.

I also find it of advantage to provide the 105 upper or outer face of the locking member or nut 5 with the spaced recesses or pockets 10^a. Insertible within the pocket 10^a is a shank 11 provided with the perforate head 12. Disposed through the head 12 is a bolt 110 14 in threaded engagement with the section 1 and interposed between the head of the

bolt 14 and the head 12 of the shank 11 is a lock washer 15. The shank 11 when operatively engaged with the locking member or nut 5 serves to hold said member or nut 5 in applied position.

From the foregoing description, it is thought to be obvious that a rigid coupling constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. In combination with the meeting ends of the sections of a drill rod having reduced extensions flaring outwardly, a sleeve comprising separable sections snugly receiving the extensions of the meeting ends of the rods, the outer surface of the sleeve being tapered in one direction throughout its length, a collar slidable over the sleeve, the bore of said collar being tapered to correspond with the periphery of the sleeve, and

a member in threaded engagement with one of the sections of the drill rod and contacting with the end portion of the collar toward which the bore of the collar tapers for holding said collar against movement in one direction.

2. In combination with the meeting ends of the sections of a drill rod having reduced extensions flaring outwardly, a sleeve comprising separable sections snugly receiving the extensions of the meeting ends of the rods, the outer surface of the sleeve being tapered in one direction throughout its length, a collar slidable over the sleeve, the bore of said collar being tapered to correspond with the periphery of the sleeve, a member in threaded engagement with one of the sections of the drill rod and contacting with the end of the collar toward which the bore of the collar tapers for holding said collar against movement in one direction, and means coacting with the rod sections and the sleeve for holding the same against relative rotation.

In testimony whereof I hereunto affix my signature in the presence of two witnesses.

WILLIAM H. BRUNSON.

Witnesses:

FRED STEPHENS,
CHARLES H. WALKER.
